8307X

Nathan Booth of Cheshire, Connecticut.

Letters Patent.

The schedule referred to in these Letters Patent and making part of the same, containing a description in the words of the said Nathan Booth himself, of his improvement in cider mills, called "Booth's improved cider mill."

To all to whom these presents shall come:

Be it known, that I, Nathan Booth of Cheshire, in the County of New Haven in the State of Connecticut, have invented a new and useful improvement in cider mills, called "Booth's improved cider mill"; and that the following is a full and exact description of the construction & operation of said machine as invented or improved by me. My improvement or invention consists in the application of the principles of the old, well known box coffee mill to the purpose of grinding apples into pomace. This I effect by enlarging the size, and I also make the box or shell, and the big cylinder as I call it, of wood, and arm each with spical bars of iron, so fixed on the shell and cylinder, as to break, but not bind them. Apples to any desirable degree of fineness in this passage through the mill. The cylinder as I call it, I make of wood, and for the ordinary size of mills, about twenty two inches long, exclusive of the shaft, twenty inches in diameter at the base, and thirteen at the top being a truncated cone, on the sides of this cylinder, I place eight iron bars, six inches wide, and half an inch thick, and about twenty four inches long, at equal distances, running round the cylinder at an angle of about twenty five degrees. The upper ends of these bars, projecting their full thickness. The lower end sink into the wood, so as to project, only one sixteenth of an inch, thereby forming the fluting or grooving, in other words the bars may be taken off to a level, down half the length of the cylinder, from thence to the base, I divide the cylinder into sixteen portions or grooves, the intermediate bar

may be of iron or wood, and the surface between them reduced accordingly. The number and length of the bars, as above is calculated, for a cylinder of the size described, if larger or smaller the number and length of the bars may be proportionally increased or lessened. From the centre of the cylinder a shaft rises perpendicular about six feet to which is attached a lever for the application of horse power. The shaft and cylinder are made of the same piece of timber, and are made upright by guides. The guides on in the upper end of the shaft is secured and plays in a cross beam above. The lower guides plays in a cross beam or lighter, which may be raised or lowered by a screw or wedge to regulate the grinding. The cylinder is surrounded on the sides, by a firm strong box or shell of wood, which I make of two pieces, of timber, each about four or five feet long, and about eighteen inches square. These timbers are hollowed out in the middle so that when firmly bolted together, they will form a box or shell around the sides of the cylinder above described, the inner diameter of which, will be about two inches larger than the diameter of the cylinder at the upper end, and about one eighth of an inch larger than its diameter at its base, and about eighteen inches in height open at top and bottom, and firmly supported over the box so as to permit the cylinder within, to be raised or lowered at pleasure as herein before described. Around the hollow of this shell on the inside are six or eight bars of iron, of about the same size, as those on the cylinder, running diagonally at an angle of about forty five degrees, and in a direction opposite to those on the cylinder, the ends and front of the bars presenting the same projections, and forming thereby, when in operation, a succession of shear to crush, and cut the apples in their descent. Openings are made between the bars, both on the shell, and on the cylinder at the upper end of the box sufficiently large to accommodate the largest apples. The iron bars are firmly secured to the sides of the cylinder and of the shell by bolts, spikes or screws, or this shell may be made in the form of a tub firmly hooped with iron.

8307

iron, or the whole shell, including its bars, or fluting, may be of
 cast iron, but will be more liable to corrosion, and therefore not
 to be preferred. The mill or machine herein described is calc-
 ulated to stand with the cylinder, and shaft, perpendicular,
 having a hopper around the shaft and over the opening with
 top to receive the apples, and a suitable cut to receive the pomace
 at the bottom, & is to be moved by horse, or other power, all in the same
 al manner, but, the mill may be placed horizontally with the
 hopper and a suitable opening on the upper side, and moved
 by water or other power. A model with drawings for illustration
 will accompany this specification. The advantages of this
 invention, or improvement are, that apples are more expe-
 diently, and more uniformly crushed and ground and the pomace
 more more perfectly and uniformly formed than is or can be
 done by any known mill, as the whole may be made to pass a
 space between the cylinder, and shell, not exceeding, if so required
 one sixteenth of an inch, and this space may be lessened or enlarged
 at pleasure. This mill thus armed with iron, is not subject to
 ordinary wear and tear, and is not liable to be injured by stones
 and stones when found in the mill can be ejected by reversing the
 motion. As the basis of my improvement and invention, is the old
 and well known box, buffered mill. I claim only as my invention
 the use of iron bars to arm wooden cylinders, and shells of proper
 size, with suitable teeth and fluting to form a strong and durable surface
 peculiarly adapted to grinding apples for cider, in the manner above
 specified, and therefore I solicit Letters Patent.

In witness whereof I subscribe this specification at New
 Haven, Conn for the date of 1834.

Witnessed

Simon Baldwin
Clerk of the Baldwin
